PROCESS FOR DESTROYING PESTS COM-
PRISING THE APPLICATION OF THE DI-
BUTYL ACETAL OF AMINOACETALDE-
HYDE TO THE PESTEmily M. Owen, Easton, Pa., assignor to General
Aniline & Film Corporation, New York, N. Y.,
a corporation of DelawareNo Drawing. Application November 19, 1948,
Serial No. 61,140

1 Claim. (Cl. 167—22)

1

This invention relates to improved methods for destroying or inhibiting the growth of insects, bacteria and the like.

It has been found that certain pests such as soft-bodied insects (aphids, mites, etc.) bacteria, fungi and the like may be destroyed, or their growth inhibited, by applying thereto a solution of a compound having the following general formula:

or

wherein R is hydrogen, NH₂, Cl, or CCl₃ and R₁ is an ethyl or butyl group and R₂ is a butyl, decyl or dodecyl group.

Examples of some of these compounds include the following:

Table

R	R ₁	R ₂
H	—C ₂ H ₅	—C ₁₂ H ₂₅
H	—C ₂ H ₅	—C ₁₀ H ₂₁ (β)
Cl	—C ₂ H ₅	—C ₄ H ₉
H,N	—C ₂ H ₅	—C ₈ H ₁₇
Cl,C	—C ₂ H ₅	—C ₁₀ H ₂₁

The compounds of the present invention have been found useful both for the destruction and inhibition of growth of soft-bodied insects, bacteria, fungi, worm pests such as nematodes and wireworms etc. and, for convenience, the material is herein designated as a biocide. The following examples illustrate the use of certain of the compounds on bacteria, spores and aphids.

Example 1

Using the "slide germination technique" described by S. E. A. McCallan et al., Contributions of the Boyce Thompson Institute 4,233 (1932); 9,249 (1938); 10,329 (1939); 12,49 (1941); 12,431 (1942), it was found a 1/100% solution of the dibutyl acetal of aminoacetaldehyde in 1% acetone completely inhibited the germination of *Sclerotinia fructicola* spores.

Example 2

Using the procedure described in Example 1, it was found that a 1/1000% solution of the tetra-

butyl acetal of iminodiacetaldehyde in 1/10% acetone completely inhibited the germination of *Sclerotinia fructicola* spores.

Example 3

When a 0.1% solution of dibutyl acetal of aminoacetaldehyde in 10% acetone was tested by the agar cup plate method as described in U. S. D. A., Circular No. 198, an 8.0 mm. zone of inhibition was shown against *Escherichia coli* and a 1.5 mm. zone of inhibition against *Staphylococcus aureus*.

Example 4

A solution containing 0.5% by weight of the dibutyl acetal of β,β,β -trichloropropionaldehyde in 50% acetone was sprayed on a potted nasturtium plant infested with *Aphis rumicis*. After 24 hours a mortality of 90% of the aphids was observed.

Example 5

A solution of 0.125% by weight of the dibutyl acetal of aminoacetaldehyde sprayed as in the above example gave 83% mortality of *Aphis rumicis*.

The acetals of the present invention are preferably used in solution in an organic solvent therefore which is also miscible in water such as ethyl alcohol and acetone. However, the compounds may be employed with inert diluents and with carriers, in solution with various solvents, emulsifying agents, in water dispersions, etc. They may be applied as dusts, sprays, washes, aerosols, dipping solutions, etc.

35 I claim:

A process for destroying pests which comprises applying thereto dibutyl acetal of aminoacetaldehyde.

EMILY M. OWEN.
